CRACKING OF PETROLEUM VAPORS

Andrew McGregor Wood, Miri, Sarawak, Borneo

Application January 14, 1931, Serial No. 508,671

8 Claims. (Cl. 196—61)

This invention relates to the conversion of heavier hydrocarbons into lighter hydrocarbons by heat and particularly to such cracking carried out in the vapor phase.

Cracking of petroleum in the vapor phase has heretofore been handicapped by difficulties caused by the method by which the vapor is brought to and maintained at the cracking temperature. Due to the very dispersed molecular nature of a gas and the consequent low conductivity, it is almost impossible under existing methods to raise to and maintain a body of vapor at cracking temperature in such way that said temperature will be uniform throughout the body, and to avoid a considerable temperature gradient between that part of the vapor next to the heat supply and that part more remote from it. For instance, if the vapor is heated in furnace tubes, the vapor passing near the inner circumference of the tube is considerably hotter than that near the center. Thus to produce a cracking temperature at the center the vapor near the tube wall must needs be overcracked with the consequent and very undesirable deposition of carbon and reduced efficiency and the burning out of tubes. Another difficulty is after the vapor has once reached cracking temperature to prevent overheating during its further progress through the tubes, as only a comparatively small amount of heat is needed to maintain this temperature, and it is difficult to control the input of heat throughout the length of the tube coil.

My invention consists of a method to maintain a uniform temperature throughout a cross section of the vapor at any point in the cracking tube, and also a small temperature gradient along the flow of vapors between any two points in said tube avoiding sudden raises of temperature or regions of too high temperature. To obtain this, I pass countercurrent to the flow of vapors, through the center of the heating tube a stream of relatively cool liquid oil or vapors through an inner concentric tube; the annular space between the two tubes is the cracking space.

The attached drawing shows by way of illustration or example one form of apparatus, adapted to carry my invention into effect: it will be understood that I do not limit myself to this particular design.

The more or less diagrammatically shown apparatus consists of: furnace 1, evaporator 2, dephlegmator 3, surge tank 4 and condenser 5.

In the operation of this apparatus, using liquid oil in the inner of the two concentric tubes, the pump 6 forces the oil through the pipe 7 into

the dephlegmator 3 from which it goes, after the removal of any light fractions, through the pipe 8 into the surge tank 4. It is then forced through the pipe 9 by the pump 10 into a coil 11 in the furnace 1, valve 15 in pipe 18 being closed. Coil 11 enters concentrically the larger coil 12, valve 19 and 20 both being closed. The liquid oil continues in the inner tube of coil 12 being progressively heated by heat transfer from the outer tube. It now leaves the furnace through pipe 13, valve 22 being closed, and enters the evaporator 2 where, with the aid of superheated steam from the open pipe 31, it is partly evaporated. The liquid residue is removed through the pipe 14. The vapor is now returned to the furnace through pipe 16 and 21 and enters the outer tube of coil 12. It passes through this tube in turbulent condition and is here subjected to cracking temperatures. The products of the reaction are then passed through pipe 17 into the dephlegmator 3 where the heavier hydrocarbons are condensed and returned to the system. The gasoline vapors then pass through pipe 24 into the condenser 5 and thence to storage.

The pipe 18 serves as a means of temperature control for the oil entering coil 12. If, at any time, the oil becomes too hot, it is only necessary to open valve 15 slightly, at the same time closing valve 25 somewhat, thus deflecting part of the oil from its path through the furnace. It is the function of the cylinder 26 to mix the hotter and cooler oil streams so that oil of even temperature enters coil 12. By this arrangement a very accurate control is obtained.

The oil to be treated is heated in coil 11 under control to a temperature of about 500° F. It is then passed through the inner tube of coil 12, where, due to heat exchange with the outer counter current flow of hot vapors, it is gradually heated to about 700°—750° F. Sufficient pressure is maintained to keep the oil in liquid condition until its release on entering the evaporator. In some cases it might be desirable to obtain some cracking in the liquid phase before the oil enters the evaporator; temperatures and velocities will then be changed accordingly throughout the system and the process conducted at a generally higher degree of heat, so that the liquid oil will enter the evaporator at say 900° F. If desired, the gasoline obtained may be separated from the heavier fractions before the vapors of the latter are passed into the outer cracking coil. Here vaporization takes place the process being assisted, if desired, by the use of super-heated steam supplied by the open steam pipe 31. Suff-

cient pressure is maintained on the evaporator to pass the vapor into the outer or cracking tube, where it is cracked, and from there to the dephlegmator 3 where the heavy or uncracked fractions are condensed and recycled, the light fractions going on to the condenser 5 where they are liquefied. The pressure on the condenser is only slight, say 30 lbs., only sufficient to handle the uncondensed gases. The temperature of the vapors on leaving the evaporator will be around 600-650° F.; this will be raised to say 1000° F. in the outer cracking tube.

If it is desired to pass vapors through the inner tube instead of liquid oil, some changes in the operation of the apparatus have to be made. Valve 25 is closed and valve 19 is opened, thus allowing the hot oil to go directly to the evaporator. After vaporization the volatile matter is returned to coil 12 through pipe 28 by closing valve 29 and opening 20 and the vapors then circulate through the inner tube. After passing through this tube they are returned directly to the outer tube for cracking, this being accomplished by closing valve 30 in pipe 13 and opening valve 22.

When vapor is used in the inner coil instead of liquid oil the temperatures on the relative parts of the apparatus are about the same. The oil from coil 11 under any necessary pressure to keep it in the liquid state, is forced into the evaporator at about 600° F. It returns as vapor to the inner tube of coil 12 at 500 to 550° F. and on leaving this tube has attained a temperature of about 700-750° F. In the return of the vapor through the outer tube the maximum temperature of about 1000° F. is reached.

A uniform temperature throughout the vapor in a cross section of the cracking tube is obtained by effecting a turbulent flow of the vapors through the tube. At a certain critical velocity the flow of vapors through a given tube will change from a stream line flow into a turbulent one, which flow will continue for all higher velocities. This critical velocity is variable with the physical characteristics of the tubes. The use of the inner concentric tube restricts the space in the cracking tube, thus increasing the turbulency without decreasing the heating surface. The turbulency consists of a whirling motion of the vapors, the centrifugal force of which will tend to throw the cooler, more dense molecules to the outside of the tube while the hotter, lighter ones will move towards the center. In this way the coolest portions of the vapor will pass nearest the heating surface, while overheating will be prevented by the circulation of the hottest portions around the inner tube carrying the relatively cool stream of hydrocarbons. The resulting heat exchange regulates the cracking tube temperature and at the same time affords heat economy by warming the incoming oils.

A very uniform temperature gradient between successive points in the cracking tube is obtained by the moderating effects of the flow of cooler hydrocarbons in the inner tube. As the hot vapors start out in the cracking tube they are in contact with the highest inner tube temperatures and as they pass along they are gradually heated by the furnace to, say, about 1000° F. At this point the inner tube is considerably cooler and an equilibrium in the heat transfer is effected so that the inner tube is absorbing as much from the outer tube as the outer tube is from the furnace, thus keeping the cracking temperature constant. Past this point, the inner tube being still cooler, will be absorbing more heat from the

outer tube than the outer tube is receiving from the furnace with the consequent gradual decline of the temperature in the outer tube until at the exit from the furnace it is reduced to, say about 750° F. The inner counter current flow in this way permits of a very effective control of cracking tube temperatures due to the ease with which its temperature is controlled by valve 15.

By changing the temperature of incoming oils the maximum cracking temperature can be varied. The point on the tube where this maximum temperature occurs can also be thus varied with respect to the ends of the tube. This is of value in operation due to the fact that the corrosional wear is greatest at the point of maximum temperature. If this point can be shifted the tube will have a longer life before it burns out.

I have specified the above temperatures and method of operation only by way of example. However, I do not limit myself to these, as many temperature combinations and operating methods are possible, based on the principle of my invention and depending on the nature of the oil to be cracked and the products desired.

I claim as my invention:

1. A process for the cracking of hydrocarbon oil in the vapor phase comprising heating a tubular stream of oil to a temperature insufficient for cracking, partly vaporizing the oil and separating resultant vapors from the liquid oil, passing the vapors thus freed from the liquid oil again through the heating zone at a cracking temperature, counter current to the stream of liquid oil in indirect heat exchanging relationship therewith, and heating the vapor stream to vapor phase cracking temperature during such passage.

2. A process for the cracking of hydrocarbon oil in the vapor phase comprising heating a tubular stream of oil to cracking temperature, partly vaporizing the oil and separating resultant vapors from the liquid oil, passing all or part of the vapors thus freed from the liquid oil again through the heating zone at a cracking temperature, counter current to the stream of liquid oil in indirect heat exchanging relationship therewith, and heating the vapor stream to vapor phase cracking temperature during such passage.

3. A process for the cracking of hydrocarbon oil in the vapor phase comprising controlling the cracking temperature of a substantially liquid-free tubular stream of hydrocarbon vapor being heated to vapor phase cracking temperature by passing a countercurrent stream of relatively cooler hydrocarbons of a controlled temperature, concentrically through the stream of vapors.

4. An apparatus for cracking hydrocarbon oil in the vapor phase comprising a furnace, a heating coil therein, an evaporator to which the heating coil is connected, an outer concentric heating coil in the furnace and surrounding the first heating coil, and means to pass vapors from the evaporator through the outer coil.

5. In a vapor phase cracking process, the method which comprises passing a stream of hydrocarbon vapors through a heating zone, heating the stream to vapor phase cracking temperature during its passage through the heating zone by indirect heat exchange with heating gases, and passing a stream of relatively cooler hydrocarbons through the heating zone countercurrent to and in indirect heat exchange relation with the vapor stream being heated.

6. In a vapor phase cracking process, the

- method which comprises passing an annular stream of hydrocarbon vapors through a heating tube, heating the vapor stream to vapor phase cracking temperature by passing heating gases over the tube, and passing a stream of relatively cooler hydrocarbons centrally through the tube countercurrent to and in indirect heat exchange relation with the vapor stream. 5
7. In a vapor phase cracking process, the method which comprises passing a stream of hydrocarbon vapors through a heating zone, heating the stream to vapor phase cracking temperature during its passage through the heating zone by indirect heat exchange with heating gases, 10 and passing a stream of relatively cooler hydrocarbons through the heating zone countercurrent to and in indirect heat exchange relation with the vapor stream being heated, heating the stream of relatively cooler hydrocarbons to the vaporizing temperature of a substantial portion thereof, 15
- discharging the thus heated stream into a vapor separating zone and separating the same therein into vapors and residue, and passing the separated vapors from the separating zone to the heating zone to constitute said stream of hydrocarbon vapors. 20
8. In a vapor phase cracking process, the method which comprises passing an annular stream of hydrocarbon vapors through a heating tube, heating the vapor stream to vapor phase cracking temperature by passing heating gases over the tube, and passing a stream of relatively cooler hydrocarbons centrally through the tube countercurrent to and in indirect heat exchange relation with the vapor stream, subsequently separating vapors from the stream of relatively cooler hydrocarbons, and passing the separated vapors to the heating tube to constitute said annular stream. 25
